TOBACCO CAN

George E. Guffey and Joseph C. Rhodes,
Danville, Ky.

Application March 2, 1936, Serial No. 66,745

2 Claims. (Cl. 206—56)

This invention relates to containers, and its general object is to provide a tobacco can of the usual shape, but which includes a false bottom that is movable vertically within the body of the can, to elevate its contents, from time to time, as it is being used so that the contents will be in convenient reach at all times until completely removed.

Another object of the invention is to provide a tobacco can with a false bottom which can be easily and expeditiously elevated to carry the contents toward the outlet end of the can, with very little effort, and without fear of injury to the fingers of the user.

15 A further object of the invention is to provide a tobacco can of the character set forth, that is simple in construction, inexpensive to manufacture and extremely efficient in use and service.

This invention also consists in certain other features of construction and in the combination and arrangement of the several parts, to be hereinafter fully described, illustrated in the accompanying drawing and specifically pointed out in the appended claims.

25 In describing our invention in detail, reference will be had to the accompanying drawing wherein like characters denote like or corresponding parts throughout the several views, and in which:—

Figure 1 is a front view of the can which forms the subject matter of the present invention.

30 Figure 2 is a vertical sectional view taken therethrough.

Figure 3 is a sectional view taken approximately on line 3—3 of Figure 1.

35 Figure 4 is a sectional view taken approximately on line 4—4 of Figure 1, looking in the direction of the arrows.

Figure 5 is a view of the false bottom or contents elevating means for the can.

40 Referring to the drawing in detail, the reference numeral 1 indicates the body of our can which is of the usual shape, in that it is relatively narrow, and the front and rear walls 2 and 3 thereof merge into curved sides 4.

45 A flanged cover 5 is hingedly secured to the rear wall, and an outwardly directed bead 6 extends about the body adjacent the upper end thereof to act as a stop or abutment means for the flange of the cover, as clearly shown in Figure 3 of the drawing.

The bottom of the can is open and the front wall is provided with an opening or recess 7 extending from the lower edge thereof and upwardly but terminates adjacent to the transverse 55 center of the body. The lower edge of the body,

as well as the edges of the opening 7 are reinforced by a bead 8 that follows the outline thereof.

5 Mounted for slidable movement within the body of the can, is a false bottom 9 of a shape and size to fit the body for slidable movement therein, and the bottom is provided with a flange 10 formed with and rising from the outer edge thereof. The portion 11 of the bead that extends about the outline of the lower edge of the body, acts as a stop for the bottom 9, and formed on the flange 10 is a shield plate 12 of a size to completely cover the opening 7, as best shown in dotted lines in Figure 1.

10 While we have illustrated the opening 7 and shield plate 12 as being substantially square, we want it understood that both may be of any desired shape that is useful for the purpose.

15 From the above description and disclosure of the drawing, it will be obvious that as the contents of the can is being removed therefrom, the false bottom can be elevated by pushing the same upwardly, consequently the contents of the can is elevated accordingly, so that it will be in convenient reach of the user at all times, or until completely removed therefrom. The bead 8 not only acts as a reinforcing means, and the portion 11 as a stop for the bottom 9, but also to prevent the user from being injured or cut by the edges of the can, as it will be apparent that such would be possible in the event the bead was eliminated. It will be further obvious that due to the opening 7, the bottom can be elevated a relatively great distance with respect to the body of the can, and to an extent whereby the entire contents can be readily removed, with very little effort.

20 It is thought from the foregoing description that the advantages and novel features of our invention will be readily apparent.

25 We desire it to be understood that we may make changes in the construction and in the combination and arrangement of the several parts, provided that such changes fall within the scope of the appended claims.

30 What we claim is:

35 1. A receptacle comprising a hollow body having open upper and lower ends, a closure for the upper end and being hinged to the body, said body having a recess in a side wall thereof extending upwardly from the open lower end, a bead following the outline of the lower end and recess respectively to reinforce the same, flanged means within the body for closing the lower end and mounted for vertical movement within the 40 45 50 55

body to elevate the contents thereof toward the upper end, and a shield carried by said flanged means for closing the recess, said shield being disposed within the body.

5 2. A receptacle comprising a hollow body open at each end, a closure for one end of the body, a movable bottom within the body, an inwardly extending bead carried by the body adjacent the opposite end, said body having a cut out portion 10 in a wall thereof opening through said opposite

end, an upwardly extending flange integral with said bottom and slidably engaging the inside of the body, and a shield integral with said flange and extending upwardly therefrom to thereby close said cut out wall portion when said bottom is in its lowermost position, said cut out portion having a width sufficient to admit at least one finger to thereby move said bottom.

GEORGE E. GUFFEY.

JOSEPH C. RHODES.
